S. GRUBER

WATCHMAKER'S PLIERS

Filed July 19, 1926

FIG. 2.

FIG. 1.

FIG. 5.

FIG. 5.

FIG. 4.

FIG. 6.

FIG. 7.

INVENTOR:

Sidney Gruber

BY David E. Carlson

ATTORNEY.

UNITED STATES PATENT OFFICE.

SIDNEY GRUBER, OF ST. PAUL, MINNESOTA.

WATCHMAKER'S PLIERS.

Application filed July 19, 1926. Serial No. 123,343.

My invention relates to improvements in pliers and the object is to provide a simple and efficient device particularly useful for watchmakers in repairing broken ends of the 5 main springs of watches.

In the accompanying drawing:

Fig. 1 is a side view of a preferred form of my improved pliers with its jaws opened.

Fig. 2 is an enlarged front view of the 10 plier jaws shown in Fig. 1 but showing the said jaws closed in the process of making an end hook on a watch spring.

Fig. 3 is a top view of a main spring barrel, the main spring and spring end holding 15 means of the type for which my device is particularly applicable.

Fig. 4 is a side elevation of the forward part of my pliers in a modified form.

Fig. 5 is a sectional view about as on 20 line 5—5 in Fig. 4.

Fig. 6 is a bottom view of Fig. 4.

Fig. 7 is a front view of the plier jaws shown in Fig. 4 and a main spring of a 25 watch in position to have its outer end formed with a hook.

Referring to the drawing by reference numerals, my pliers are made in comparatively small size consisting of any suitable type of crossed members pivoted at 10 rearwardly of 30 which are the handles designated as 11 and 12, 11 being integral with the lower jaw 11^A and 12 being integral with the upper jaw 12^A. Jaw 12^A is in all cases a thin member with a downwardly directed extremity 13 of 35 wedge shape. The lower jaw 11^A comprises a longitudinally slotted member providing an elongated opening 25 into which the wedge 13 is pressed by closing the handles 11—12. Adjacent the slit of the lower jaw 40 one side of it has a horizontal ledge 14 and an adjoining vertical flange 15 forming with said ledge a square pocket 16 in conjunction with the inner transverse ledge 15^X across the lower jaw. A gage sleeve 17 may be 45 slipped on the lower jaw member and stopped against the transverse ledge 15^X of flange 15. The thickness of sleeve 17 reduces the area of the slot in the lower jaw 50 into which wedge 13 is moved.

Fig. 3 shows a top view of a main spring barrel 18 in which is fixed at the center (not shown) the main spring 19. In some makes of small watches, such as so-called Swiss watches, the outer end of spring 19 is formed

with an outwardly opening hook 20 engaged 55 by one end of a loose bar 21 of flat material. The other end of bar 21 engages in a slot or pocket 22 of the barrel 18. This bar is simply a compensating link to maintain connection between the spring and the barrel 60 at all times. It is the object of my improved pliers to make the hook 20 on either broken or new main springs. This is done by simply heating the spring end to soften it then laying it on ledge 14 and against 65 ledge 15^X with its extreme end against the flange 15, as shown in dotted lines in Fig. 2. Thus the heated end of the spring lies across the slotted part of the lower jaw and the wedge part 13 of the upper jaw is quickly 70 brought down into the slit and thus bending the spring end into an open hook shape between the jaw members 11^A (see full line showing of spring 19 in Fig. 1). This hook making process must be accomplished very 75 rapidly while the heated spring end is very pliable.

In the modification Figs. 4 to 7 inclusive, the lower jaw is elongated and bifurcated to form two parallel members 11^B and 11^C, 80 the former having the ledge 14 and the L-shaped flange 15 at its front end. 22 is a thumb-screw inserted loosely in one jaw and threaded into the other jaw to close them or spring them toward each other as desired according to the thickness of the watch spring 85 and the amount of opening of the hook 20 desired. This form of my device has light preferably tapering jaws which may be inserted in a flame with the spring end in 90 place to be bent and the jaws closed when the spring has been properly heated in the flame.

The use of my improved pliers has been 95 fully disclosed in the foregoing specification.

What I claim is:

1. A plier of the class described comprising two pivotally connected members each comprising an integral handle and a jaw, 100 one of said jaws formed with a wedge-shaped extremity directed toward the other jaw, the other jaw having a slotted portion to receive said wedge when the pliers are closed, an upright longitudinal flange on 105 the outer part of the slotted jaw in spaced parallel relation to the slit, said flange having a transverse extension across the jaw to

form a square corner for insertion of the end of a watch spring while the jaws are open, and means for selectively spreading or closing the slotted part of the lower jaw.

5 2. The structure specified in claim 1, in which said spreading and closing means for the lower jaw comprises an adjusting screw

inserted loosely in an aperture in one of the jaw sections and threaded into the other section to spring said jaw sections toward each other and close their forward ends according to the width of slit required.

10 In testimony whereof I affix my signature.

SIDNEY GRUBER.
